CLAIM

The ornamental design for a tote bag, as shown and described.

DESCRIPTION

FIG. 1 is a perspective side view of a tote bag showing our new design;

FIG. 2 is a front elevational view of the tote bag;

FIG. 3 is a back elevational view of the tote bag;

FIG. 4 is top plan view of the tote bag;

FIG. 5 is bottom plan view of the tote bag;

FIG. 6 is a right side view of the tote bag; and,

FIG. 7 is a left side view of the tote bag.

The lighter broken lines of the tote bag depict stitching and are part of the claimed design. The bold broken lines depict parts of the tote bag that form no part of the claimed design.

1 Claim, 6 Drawing Sheets
